To all whom it may concern:

Be it known that I, Tora Coleman, a citizen of Latvia, residing in the city of New York, county of New York, and State of New York, have invented a new, original, and ornamental Design for a Dress Ensemble, of which the following is a specification, reference being had to the accompanying drawing, forming part thereof.

The characteristic feature of my design resides in the combination on the specific ensemble disclosed of the specific patches of embroidery on the dress blouse and on the front and rear shoulders of the jacket as shown.

I claim:
